DESIGN FOR A BILLFOLD

Jacques Schwalbe, New York, N. Y.

Application June 8, 1940, Serial No. 92,897

Term of patent 7 years

To all whom it may concern:

Be it known that I, Jacques Schwalbe, a citizen of Belgium and residing at the city, county, and State of New York, have invented a new, original, and ornamental Design for a Billfold, of which the following is a specification, reference being had to the accompanying drawing, forming part thereof.

The end pieces are of metal. The back, that is, the outside when the billfold is folded, is substantially plain.

I claim:

The ornamental design for a billfold, substantially as shown and described.

JACQUES SCHWALBE.
